UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

ANTIFRICTION BEARING.

Application filed February 5, 1926. Serial No. 86,159.

This invention relates to improvements in anti-friction bearings.

The object of the invention is to provide an efficient anti-friction bearing especially fitted for use as a side bearing on railway cars and wherein the anti-friction element proper is always automatically returned to central normal position when freed from load.

10 In the drawing forming a part of this specification, Figure 1 is a vertical, sectional view taken through the ends of the body and truck bolsters of a railway car showing my improvements in connection therewith. Fig. 15 2 is a bottom plan view of the side bearing proper shown in Fig. 1. And Fig. 3 is a vertical, sectional view corresponding substantially to the section line 3—3 of Fig. 1.

In said drawing, 10 denotes the upper 20 portion of a truck bolster and 11 the under portion of an opposed body bolster of a railway car. My improved bearing is shown attached to the body bolster and comprises, broadly, a base casting, retaining member or 25 housing A; an anti-friction element proper B; a pair of springs C—C; a pair of spring followers D—D; and a pair of links E—E.

The housing A is in the form of a box 30 having top wall 12, depending vertical side walls 13—13 and curved end walls 14—14, the housing being open at the bottom to permit the anti-friction element proper to project therethrough. The side walls 13 are provided each with a lateral off-set 13^A of 35 circular form. Each of the lateral off-set portions 13^A is further formed with a laterally extended vertically disposed guide groove 15, the latter being adapted to be closed at the bottom by a threaded plug 16, 40 as shown in Fig. 3. Preferably, a hardened wear or bearing plate 17 is inserted within the housing A at the upper side thereof, said plate being held in position by rivets 18.

The anti-friction element proper, B, is 45 shown as of true cylindrical form, although, as will be evident to those skilled in the art, the shape of this element may assume other forms. Said element is adapted to have rolling contact with the bearing plate 17 at 50 the top and with the upper surface of the truck bolster at the bottom.

Disposed in each of the guides 15 is a 55 spring C, the latter being in the form of a coil with the axis thereof extending vertically so that said spring is adapted to be

compressed in a vertical direction, that is, in a direction at right angles to the line of bodily movement of the element B. Each of said springs is supported at the bottom by the plug 16, each of the latter preferably 60 having a centering boss 19 for the spring.

Also mounted in each of the guides 15 and on top of the corresponding spring C, is a spring follower block D, the latter having straight sides so that it is guided vertically as hereinafter explained.

65 The roller or element B is centrally apertured as indicated at 20, within which aperture is received a pin 21, the latter having its ends extending beyond the ends of the element B. The ends of said pin 21 are pivotally associated with the two links E, as clearly shown in Fig. 3. The upper end of the links E, on their outer sides, are provided each with a pivot lug 22 entered within a 70 corresponding opening 23 provided in the corresponding follower D. The pin 21 is inserted through a suitable opening 24 in one of the side walls of the housing A before the wear plate 17 is applied so that, when 75 the plate 17 is in position, the pin 21 can never assume a position opposite said opening 24, thereby retaining all of the parts in 80 assembled relation.

85 The normal position of the parts is as shown by full lines in Fig. 1 where it will be noted that the links E assume a vertical position with the pivotal connections thereof in vertical alinement and the springs C in their most extended position. When the anti-friction bearing is moved to either side of 90 normal central position, as, for instance, to the dotted position at the right-hand end of Fig. 1, it is evident that the pin 21 will travel in a horizontal line and consequently 95 the pivot lugs 22 of the links E will be pulled downwardly since they are associated with the followers D which are confined to a straight vertical line movement. In this manner the springs C are placed under comp-

100 pression and hence, when the element B is relieved of load, the spring C will expand, force the followers D upwardly within the vertical guides, and thus induce the links E to assume their normal vertical position and 105 in turn restoring the element B to its central position ready for a succeeding actuation. In this connection it will be observed that the opposite sections 13^A of the side walls provide the necessary clearance for the 110

swinging movements of the links E. Preferably, the end walls of the housing A will be so formed and located as to determine the limit of rolling movement of the anti-friction element.

I have herein shown and described the preferred manner of carrying out the invention, but the same is merely illustrative and all changes and modifications are contemplated that come within the scope of the claims appended hereto.

I claim:

1. In an anti-friction bearing, the combination with a housing having side and end walls, and a bearing surface, the side walls of said housing being provided with vertically arranged guideways extending from points adjacent the free extremities of each of said side walls inwardly to and terminating substantially at said bearing surface; an anti-friction element disposed within said housing and adapted to roll back and forth on said bearing surface, said element being of greater extent than the extent of said side walls, so as to project beyond the free extremities of the latter when in engagement with said bearing surface; followers slidably disposed in said guideways, a coil spring disposed in each of said guideways, and links connected to said anti-friction element and to the said followers, whereby

movement of said anti-friction element to either side of central position flexes said springs which operate to return said element to central position, said followers, springs, and links being interposed between the side walls of said housing and the adjacent ends of said anti-friction element.

2. In an anti-friction bearing of the character described, the combination with a housing adapted to be secured to a body bolster, and provided with depending side walls and a bearing surface, said side walls having vertically arranged guideways therein; of spring means supported in said guideways; followers supported upon the upper ends of said springs; an anti-friction element arranged in said housing and adapted to engage said bearing surface, said anti-friction element being adapted to co-operate with an opposing truck bolster; and links connecting said followers and said anti-friction element for supporting the latter in said housing in contact with said bearing surface, movement of said anti-friction element to either side of central position serving to flex said springs which operate to return said anti-friction element to central position.

In witness that I claim the foregoing I have hereunto subscribed my name this 26th day of January, 1926.

JOHN F. O'CONNOR.
